UNITED STATES PATENT OFFICE.

JOHN GLINKA, OF WILSON, PENNSYLVANIA.

SHIP-PROTECTOR.

1,294,789.

Specification of Letters Patent. Patented Feb. 18, 1919.

Application filed July 24, 1918. Serial No. 246,544.

To all whom it may concern:

Be it known that I, JOHN GLINKA, a citizen of Russia, residing at Wilson, in the county of Allegheny and State of Pennsylvania, have invented certain new and useful Improvements in Ship-Protectors, of which the following is a specification.

The primary object of the invention is the provision of adjustable outrigger members adapted for stabilizing a ship as well as protecting the hull thereof against injury from oncoming missiles, the device being serviceable at either side of the hull and also adapted for preventing other ships from contacting and damaging the hull.

A further object of the device is the provision of an outwardly positioned protector carried by a hull positionable horizontally when not in use, but readily projected to an inclined position partially immersed in the water when desired as a guard against torpedoes and other missiles.

With these general objects in view, the device consists in the novel combination and arrangement of parts hereinafter fully described in connection with the accompanying drawings and in which like reference characters designate corresponding parts throughout the several views.

In the drawings,

Figure 1 is a top plan view of a hull partially broken away with my device installed thereon;

Fig. 2 is a vertical transverse sectional view of the same;

Fig. 3 is an enlarged view partly in section and partly in elevation showing one set of operating gear connections;

Fig. 4 is a vertical sectional view thereof;

Fig. 5 is another vertical sectional view of the same taken upon a different plane from the line of section of Fig. 4.

Referring more in detail to the drawings, my invention will be illustrated in connection with the hull 10 of a ship designed to be protected from oncoming missiles by means of my invention. A perforated armor plate 11 is adjustably carried at each side of the hull 10 for partial immersion in the water after the manner of an outrigger. Each plate 11 is provided with two arms 12 having a hinge connection 13 with a rack 14 slidably mounted upon rollers 15 within a tubular rectangular casing 16 extending

transversely of the hull 10 and projecting 55 outwardly of one side thereof.

The racks 14 of each plate 11 are adapted for simultaneous operation by means of gears 17 carried by a shaft 18 journaled longitudinally within the hull 10, it being evident that upon turning the shaft 18 in opposite directions, the racks 14 will be moved inwardly and outwardly of the casings 16 imparting a corresponding movement of the arms 12 and the plate 11 carried by the said arms. Cables 19 are attached as at 20 to the plate 11 and pass over sheaves 21 provided in openings 22 of the hull 10 and thence over idlers 23 within the hull for winding upon drums 24 carried by a shaft 70 25 positioned longitudinally of the hull above the shaft 18.

A stub-shaft 26 is journaled adjacent one end of the shaft 25 having a pinion 27 in constant mesh with a gear 28 upon said shaft 25. The stub-shaft 26 is journaled in slots 29 in bearing posts 30 while the reduced ends 31 of the shaft 25 are journaled in slots 32 in posts 33 positioned adjacent the opposite ends of said shaft 25. When 80 the pinion 27 and gear 28 are in their lowered positions with the shafts 25 and 36 lowered, the gear 28 will be in mesh with the gear 17 of the shaft 18 so that upon turning the crank 34 of the stub-shaft 26, the racks 85 14 will be reciprocated simultaneously with the unwinding of the cables 19 from the drums 24 when the racks 14 are being projected and winding up the cables 19 upon said drums when the racks 14 are being retracted.

It is desirable, however, to permit the arms 12 and its plate 11 to lower into the water at an inclination when the racks 14 are projected, and this is permitted by disengaging the gear 28 from the gear 17 by means of plates 35 adapted for vertical movement upon the posts 33. Such disengagement of the gear 28 from the gear 17 also permits the arms 12 to be elevated to 100 their horizontal positions, as indicated by dotted lines in Fig. 2 of the drawings, prior to retracting the racks 14 with the said arms 12. The plates 35 have the reduced ends 31 of the shaft 25 journaled in perforations 36 of said plates while bolts 37 carried by the posts 33 freely extend through limiting guide slots 38 provided through said plates.

An operating lever 39 is provided for each plate 35 being pivoted thereto as at 40 and also pivoted to a bracket 41 carried by the adjacent post 33.

- 5 The racks 14 are normally retracted as well as the arms 12 and at which times the plate 11 will be vertically positioned adjacent the outer free ends 42 of the casings 16 slightly spaced from one side of the hull 10. The pinion 27 being in mesh with the gear 28 and the latter meshing with the gear 17, it will be seen that upon turning the crank 34 in the required direction, the shaft 25 will be revolved for unwinding the cables 19 from the drums 24 while the gears 17 project the racks 14 outwardly of the casing 16. When the plate 11 is at the outward limit of its movement, the levers 39 will be depressed for elevating the plates 35 carrying the shaft 25 and stub-shaft 26 therewith and disengaging the gears 17 and 28. The crank 34 may then be turned for permitting a further unwinding of the cables 19 from the drums 24 allowing the plate 11 to lower to the desired extent into the water at the side of the hull 10. It will be understood that by substantially reversing the operation just described, the plates 11 may be elevated positioning the arms 12 horizontally in alignment with the racks 14, and upon releasing the levers 39 the crank 34 may be turned for reversely revolving the gears 17 to inwardly move the racks 14 while the drums 24 are simultaneously revolved for winding up the cables 19. Rack portions 43 are provided for the arms 12 forming continuations of the racks 14 for meshing with the gears 17. When retracting the arms 12, the levers 39 may be held downwardly in any desired manner for maintaining the plates 35 elevated, and when the arms reach the horizontal positions, the levers 39 may be released for continuing the operation of the crank 34. An adjustable bearing block 44 is preferably provided within each slot 29 of the post 30 for bearing upon the stub-shaft 26 when the same is depressed, thereby maintaining the shaft 25 in its lowered position and the pinion and gears in meshing relations. Operating screws 45 are provided for said blocks 44 and whereby the blocks 44 are readily elevated when it is desired to elevate the stub-shaft 26.

The plates 11 are designed to be at least thirty feet outwardly of the hull 10 when operatively positioned and to extend a sufficient depth beneath the surface of the water to be hit by torpedoes traveling at their usual level toward the hull 10. The contacting of one of the plates 11 by a torpedo is designed for exploding the torpedo while it is also designed to stop the forward movement of other oncoming missiles or projectiles, and the distance at which the

plates 11 are positioned from the hull 10 is designed to be sufficient to prevent any injury to the ship by reason of such explosion or contact.

A strong protector is provided for the hull 10 which will not impede the travel thereof when the plates 11 are pivoted, while the said plates afford means for preventing a boat of the enemy from contacting the hull 10 in whatever position the said plates 11 may be located. Each plate 11 is operated separately by identically the same form of mechanism and one plate may be elevated while the other plate 11 is lowered. The transverse casings 16 for the racks 14 of the opposite plates 11 are preferably formed after the manner of a double casing as best illustrated in Fig. 3 of the drawings and with the separate casing portions projecting through the opposite sides of the hull 10 for accommodating the racks and arms of the opposite plates 11.

What I claim as new is:—

1. A protector for hulls comprising racks transversely positioned upon the hull shiftably through the side thereof, arms hinged to the outer ends of said racks, an armor plate carried by the outer ends of said arms, drums journaled upon the hull, cables carried by said drums and attached to said plate whereby said plate is adapted to be elevated or lowered when the arms are at the outward limit of their travel, operating gears for the said racks, and means adapted for operatively connecting the said drums and gears when the plates are elevated.

2. A protector for hulls comprising racks slidably mounted through the side thereof, a longitudinal shaft within the hull, gears upon said shaft in constant mesh with said racks, toothed arms hinged to the outer ends of the racks adapted for longitudinal alignment therewith during the projecting and retracting of the racks, an armor plate carried by the outer ends of said arms, an intermediate gear vertically shiftably mounted within the hull adapted for meshing with said shaft gear when lowered, a vertically movable operating pinion in constant mesh with said intermediate gear, winding drums adapted for turning with said intermediate gear, cables attached to said plate and wound upon said drums, and elevating means for said intermediate gear and pinion whereby the drums are adapted for operation either independently or simultaneously with the movement of said racks.

3. A device of the class described comprising in combination with a ship's hull, double casings transversely positioned within the hull having opposite portions thereof projecting from the opposite sides of the hull, longitudinally shiftable racks within the casing portions, arms hinged to the outer ends

of said racks, armor plates carried by the outer ends of said arms protectingly positioned at all times outwardly of the hull, means upon the hull adapted for elevating 5 said plates and permitting them to lower into the water at will, operating means within the hull adapted for projecting and re- tracting the said racks, and detachable operative connections between the said elevating and rack-operating means adapted for co-¹⁰ operation when in engagement for inwardly moving the plates toward the hull.

In testimony whereof I affix my signature.
JOHN GLINKA.
